Primary Examiner — Barbara Fox*Assistant Examiner* — Harold E Blackwell, II(74) *Attorney, Agent, or Firm* — William H. Honaker;
Dickinson Wright PLLC(57) **CLAIM**

The ornamental design for a shelf bracket as shown and described.

DESCRIPTION

FIG. 1 is a perspective view of the shelf bracket of the present invention.

FIG. 2 is a first end view thereof.

FIG. 3 is a second end view thereof.

FIG. 4 is a first side view thereof.

FIG. 5 is a second side view thereof.

FIG. 6 is a top view thereof; and,

FIG. 7 is a bottom view thereof.

The shelf bracket is shown with a symbolic break in its length. The appearance of any portion of the article between the break lines forms no part of the claimed design.
